Specification of Letters Patent. Patented Dec. 19, 1916.

Application filed June 28, 1913. Serial No. 776,238.

To all whom it may concern:

Be it known that I, HOWARD D. COLMAN, a citizen of the United States, residing at Rockford, in the county of Winnebago and 5 State of Illinois, have invented certain new and useful Improvements in Warping Apparatus, of which the following is a specification.

This invention relates to apparatus for 10 winding yarn from individual yarn masses upon a warp beam.

The invention is herein exemplified in an apparatus wherein the individual yarn masses rotate to deliver the yarn, but certain features of the invention are applicable to other types of warping apparatus. The individual yarn masses may be of various forms, as, for example, spools or cylindrical cheeses. As ordinarily practised, such warping 15 is conducted at a speed of about sixty yards a minute. If a much greater speed than this is attempted, the cheeses or spools will ordinarily coast so much farther than the beam at the time of each stop that the rise-roll or fall-roll of the warper is unable 20 to take up the slack. This difficulty may be overcome by putting a fly wheel on the warper so that the beam will coast farther than the farthest-coasting cheese, but this 25 would cause the warper to run so long after a thread breaks that the end of the broken thread would be wound under too far, and the warper tender would either not be able to find the lost end at all, or if found, she 30 would in most cases probably not be able to tie it up without introducing a crossed thread. In ordinary practice, when the velocity is about sixty yards a minute, the spools 35 will coast perhaps three or four yards, and the beam about a yard or a yard and a half less, the difference being taken up by the slack-take-up roll of the warper. If the velocity 40 is to be increased to several times the usual speed, the amount of coasting will become 45 very great since the coasting increases in proportion to the square of the velocity, but on account of the difficulty in finding and properly tying up the end of the broken thread, it is impracticable to permit of a 50 considerable increase in the amount of coasting of the beam. It is also impracticable to allow any considerable difference between the amount of coasting of the beam and the

amount of coasting of spools, since the amount of slack to be taken up by the slack-take-up roll cannot be materially increased 55 on account of limitations of space.

The object of this invention, generally stated, is to provide a warping apparatus by means of which warping may be done at 60 a very high speed as compared with ordinary warpers, say a speed several times the ordinary speed. This object is attained by providing a comparatively powerful individual brake for each cheese, each brake being of such character as to cause a large cheese to be stopped nearly as quickly as a small one, and each brake also being of practically constant efficiency; by providing automatic means for adjusting the cheese-brakes as the cheeses decrease in diameter; 65 by providing automatic mechanisms for adjusting the beam brake to take care of wear and other factors affecting the beam-brake surfaces, and for tightening the brake as the size (and hence the momentum) of the yarn mass on the beam increases, the beam-brake and its adjusting mechanism permitting an amount of coasting of the beam nearly uniformly less at each stop than the average 70 amount of coasting of the cheeses at that stop; and by providing an individual thread slack-take-up device to take up the slack which is caused by the fact that the cheeses 75 coast a little more than does the beam. 80

Patent No. 381,164, issued April 17, 1888, upon an application filed by E. E. Orrell, discloses an attempt to increase the speed of warping by the use of intermittently-applied brakes on the yarn masses. In the Orrell 90 machine, however, the brakes are applied on the heads of the spools, and no means is disclosed for making the braking effects on different spools uniform with each other. On the contrary, with the construction disclosed in said patent the braking effect 95 would be so great on some spools as to break the yarn running from them without any braking effect at all being supplied on other spools.

Orrell intended to use his device not only to prevent excessive coasting at the time of stopping, but also to make the tension on his yarn uniform from full to empty spools. Even if his device is adequate to accomplish 105 this latter purpose so far as the average ten-

sion of all the threads is concerned, there is no attempt to make the tension of the threads equal to each other. The flexibility of the pads M^2 shown by Orrell would be ¹⁰ inadequate to make the tension of the threads equal to each other, because even though an absolutely uniform pressure were applied to all the spool brakes, there still would be a very great variation in the friction, for ¹⁵ the reason that the different spool heads and their corresponding brakes would wear differently, and would present surfaces of different characteristics as to friction, so that the braking effect would be different on ²⁰ different spools, and consequently the tension would be different in different threads.

I avoid the difficulties which render the Orrell construction impracticable, by means so arranged that the pressure applied to the ²⁵ brake on each cheese is furnished by the weight of the cheese itself, a large cheese being thus caused to stop nearly as quickly as a small one. At any given stop, each cheese coasts about the same amount as all the other cheeses, because the cheeses are all approximately the same size, and because of the character of the braking surfaces. One of these surfaces is the surface of the yarn mass and the other is a polished metal plate. This plate ³⁰ is polished to start with, and the rubbing of the yarn against it in stopping keeps it bright, so that the surface condition of the plate remains very nearly constant. As stated, the other braking surface is the yarn and as a new surface is constantly being presented to the brake (owing to the unwinding of the yarn) there is no change in the characteristics of this surface due to wear, ³⁵ and other changes due to such causes as temperature and humidity affect all of the cheeses alike. On account of these circumstances and conditions, the coasting of the cheeses even when stopping from a very high speed is nearly uniform.

⁴⁰ To take up the difference between the largest amount of coast and the smallest amount of coast, I provide an individual thread slack-take-up consisting of detectors suspended on the individual threads, and ⁴⁵ an individual tube for each detector, each detector dropping in its tube as much as is required to take up the slack in its particular thread. In a warper embodying my invention and designed to operate at a speed ⁵⁰ several times as great as the ordinary velocity, these tubes may be about five feet long. As each detector takes up an amount of slack equal to twice the distance it falls, tubes of this length afford a considerable ⁵⁵ margin of safety. A part of this margin is used, however, to allow for the fact that it is impossible to stop the beam with an absolutely uniform amount of coasting. The ⁶⁰ brake on the beam is adjusted so that the thread from the cheese which coasts the least

will have some slack in it to be taken up by its detector, and so that the thread from the cheese which coasts the most will not reach the bottom of its tube, the aim being to have the beam stop so that the average ⁷⁰ position of the detectors after they have fallen in taking up slack is about the middle of the tubes. The automatic beam-brake-adjusting devices before referred to are provided so as to maintain this adjustment by ⁷⁵ correcting continuously for wear or other causes which produce changes in the frictional characteristics of the surfaces of the beam-controlling brake. The automatic beam-brake-adjusting mechanisms also ⁸⁰ include means for tightening this brake as the beam fills, so as to make a full beam coast a little less than an empty one, to allow for the fact that full cheeses coast a little more than empty ones. If this correction were ⁸⁵ not introduced, a full beam would coast more than an empty one.

In the accompanying drawings, Figure 1 is a fragmental front elevation of a warper embodying the features of my invention. ⁹⁰ Fig. 1^a is a detail view of a portion of the clutch mechanism. Fig. 2 is a fragmental top plan view of the warper. Fig. 3 is a side elevation of the warper taken from the left-hand side of Fig. 1, the driving mechanism being omitted. Fig. 4 is an elevation of the opposite side of the warper. Fig. 5 is a top plan view of the driving mechanism. Fig. 6 is a front elevation of the driving mechanism, a portion being shown in section. ⁹⁵ In Figs. 5 and 6 the mechanism is shown in position for high speed. Fig. 7 is a fragmental vertical sectional view of the driving mechanism in position for low speed. Fig. 8 is a sectional view through the clutch, taken in the plane of dotted line 8—8 of Fig. 9. Fig. 9 is a fragmental vertical sectional view similar to Fig. 7, but showing the clutch mechanism in thrown-out position. Fig. 10 is a section on line ¹⁰⁰ 10—10 of Fig. 8. Fig. 11 is a section on line 26 of Fig. 9. Fig. 12 is an elevation of the driving mechanism as viewed from the right-hand side of Fig. 5. Fig. 12^a is a section on dotted line α in Fig. 12. Fig. 13 is a ¹⁰⁵ view in the vertical plane of line 13—13 of Fig. 5, but showing the parts in a different position. Fig. 14 is a vertical sectional view taken on line 14—14 of Fig. 13. Fig. 15 is a ¹¹⁰ vertical sectional view of the detector and slack-take-up mechanism on the plane of dotted line 15—15 of Fig. 2. Fig. 16 is a section on line 16—16 of Fig. 3. Fig. 17 is a ¹¹⁵ view of a means for adjusting the brake for the warp beam, the view being taken on dotted line 17—17 of Fig. 18. Fig. 18 is a fragmental top plan view of said brake and various devices for operating the brake. The parts shown in Fig. 18 appear in side ¹²⁰ elevation in Fig. 4. Figs. 19 to 26 illustrate ¹²⁵

means for preventing the yarn mass on the warp beam from becoming eccentric. Figs. 27 to 34 further illustrate the braking mechanism for the warp beam. Fig. 27 is an enlarged side elevation of the brake for the beam. Figs. 28, 28^a and 28^b are top plan views showing different positions of a mechanism for adjusting the brake. Fig. 29 is a section on line 29 of Fig. 27. Fig. 30 is a section on line 30 30 of Fig. 31. Fig. 31 is a detail of a means for adjusting the brake-adjusting mechanism. Fig. 32 is a section on line 32 32 of Fig. 27. Fig. 33 illustrates a portion of the brake-adjusting mechanism. Fig. 34 is a section on line 34 34 of Fig. 33. Fig. 35 is a fragmental top plan view of the mechanism for throwing out the clutch through which the warp beam is rotated. A portion of the structure shown in Fig. 35 is also shown in Fig. 5. Figs. 36 to 39 are views of the detectors and the tubes in which they are located. Figs. 40 and 41 illustrate a receptacle for the fallen detectors. Fig. 42 is a fragmental side view of the creel. Fig. 43 is a fragmental view of one of the cheese supports and the corresponding brake. Figs. 44 and 45 are sectional details of the creel construction. Fig. 46 is a view of a portion of the creel-brake operating mechanism.

The embodiment herein shown of the invention is arranged to operate upon yarn masses of the form termed "cheeses," but it will be understood that the invention is not limited to use with such yarn masses.

A "cheese" (1, Fig. 42) comprises yarn wound spirally upon a tubular core 2. The cheeses are rotatably mounted in a creel positioned in front of the warper. For a detailed description of a suitable form of creel, reference may be had to my copending application Ser. No. 776,237, filed June 28, 1913. The portion herein shown of the creel comprises a rigid frame in which are arranged a plurality of "trees" upon which the cheeses are supported for rotation.

The cheeses are supported upon bushings or spindles 3 of wood or other suitable material. The spindles are each rotatably mounted upon a pivot pin 4 fixed to a guide sleeve 5 slidably mounted on the tree bar 6. All of the sleeves 5 on said bar are supported by a bar 7 having vertically elongated openings 8 to receive lugs 9 (Fig. 45) on the sleeves. The bar 7 is connected to one arm of a bell-crank lever 10. The series of bell-crank levers is supported in the creel framework. The other arms of said bell-crank levers are arranged to be moved by a rod 11 which is connected to a bell-crank 12. The bell-crank 12 is arranged to be moved by the warper, for a purpose which will presently appear.

The cheese brakes comprise polished metal plates 13 fixed to the trees in position to

underlie the respective cheeses. When the cheeses are to be stopped, the bell crank 12 is released, whereupon the bars 7 and the cheeses drop, the cheeses coming into peripheral contact with the plates 13.

As hereinbefore indicated, the cheese-supporting sleeves 5 are loosely connected to the bars 7 by means of the lugs 9 extending through slots 8 in the bars 7. When the cheese brakes are to be applied, the bars 7 are permitted to move down far enough to allow every cheese to rest upon its plate 13, but not far enough to bring the upper end wall of any slot 8 into contact with a lug 9, thus insuring that the braking pressure applied to each cheese shall be that due only to the weight of the given cheese, its bushing 3, spindle 4 and sleeve 5. The slots 8 also allow for any slight differences in the diameter of the cheeses.

Means to be hereinafter described acts to lower the cheeses as they are unwound, in order to maintain them at a uniform distance from the braking plates 13, and thus render substantially constant the time required to bring the cheeses into contact with said plates, and minimizing the shock caused by the dropping of the cheeses. A series of vertical thread-guiding bars 14 is stationarily supported at the outer side of the creel, said bars being notched, as shown, to retain the strands in definite position.

The means for applying the creel brakes when a thread breaks comprises a rod 15 (Figs. 4, 18 and 42). When the creel comprises two sections, as shown in my said copending application, a rod 15 is provided for each section, each rod being connected to a bell crank 16. The bell cranks 16 are pivotally mounted upon an arm 17 fixed to a shaft 18 (Fig. 4). This arm is automatically adjusted in position for a purpose to appear hereinafter. The bell cranks 16 are connected by rods 19 to two arms 20 (Fig. 18) rigidly mounted on a rock shaft 21. Fixed to the shaft 21 is an arm 22 which is connected by a link 23 (Fig. 46) to an arm or bracket 24 loosely mounted on a continuously rotated shaft 25. Journaled in said bracket is a pivot pin 26 to which is fixed an arm 27 carrying a stud 28. On a rock shaft 29 is fixed an arm 30 which is provided with a lateral projection 31 (Fig. 5) against which the stud 28 is arranged to bear. When the stud 28 bears against the projection 31 (as indicated in dotted lines in Fig. 46 and in full lines in Fig. 5), the bracket 24 is supported against the influence of gravity, thereby holding the cheeses off the brake plates 13. When a thread breaks, the arm 30 is swung downwardly to carry the projection 31 out from under the stud 28, whereupon gravity causes the bracket 24 to swing down into the position represented in full lines in Fig. 46, the cheeses drop-

130

ping onto the brake plates 13. The arm 30 is moved out of supporting relation to the stud 28 by means to be now described.

Fixed to the shaft 29 is an arm 32 (Figs. 3 and 46) which is connected by a rod 33 to a bell crank 34 supported on a stationary bracket 35. Attached to one arm of the bell crank 34 is a rod 36 carrying a nut and washer or other projection 37. The rod 36 is preferably screw-threaded for a considerable distance, in order to permit adjustment of the position of the nut. A weight 38 is slidably mounted on the rod 36. This weight is provided with a hanger 39 which 15 is normally supported by a rod 40 (Fig. 35). One end of the rod 40 rests on a bracket 41 and the other end is connected to an arm 42 fixed on a shaft 43. Also fixed to said shaft is a bell crank 44 (Fig. 4) arranged to be 20 moved by a spring 45. The bell crank 44 is normally held against the force exerted by said spring by a lever or detent 46 having a stop shoulder 47 against which the bell crank bears. Such detent is arranged to be raised 25 to release the bell crank by an electromagnet 48, the armature of which is attached to said detent. The electromagnet is energized whenever a thread breaks, which result is attained by the means to be now described.

30 Referring to Figs. 2 and 15: The threads extend from the guide bars 14, through a comb 49, over a roll 50, through detectors 51 and over guides 52, thence through a comb 53 and over a roll 54 to the warp beam A. Each detector 51 is located in a vertically extending tube or conduit 55. Contact bars 56 carried by arms 57 fixed on shafts 58 normally extend within openings 59 in the tubes 55, into position to arrest any 35 detector that may drop. Said contact bars are included in the circuit of the magnet 48. When a thread breaks, its detector drops into contact with the adjacent contact bar 56, thereby establishing a grounded circuit 40 through the electromagnet. The bell crank 44 is thereby released to the action of the spring 45, whereupon the shaft 43 is turned clockwise as viewed in Fig. 4. The rod 40 is thereby slid out of engagement with the 45 eye of the hanger 39, whereupon the weight 38 drops. When the weight strikes the projection 37, it tilts the bell crank 34, the movement of which is transmitted by the rod 33 and arm 32 to the shaft 29. The arm 30 is 50 thereby withdrawn from the stud 28, whereupon the cheeses drop upon the brake plates 13, the bracket 24 assuming the position shown in full lines in Fig. 46.

The brake for the beam A is applied by 55 the movement of the shaft 43 caused by the spring 45, as will appear more fully herein-after. In the present embodiment of the invention, it is desirable that the application of the beam brake occur before the cheese

brakes are applied. This result is attained 65 by the use of the weight 38 to withdraw the cheese brake detent 30, the length of the interval between the application of the beam brake and the application of the cheese brakes being regulated by adjusting the position of the projection 37 on the rod 36. I would have it understood, however, that other means may be used to cause application of the cheese brakes after the beam 70 brake has been applied, and that in other 75 embodiments of the invention the beam brake and the cheese brakes may be simultaneously applied.

The shafts 58 are connected by gear segments 60 (Fig. 3). To one of said shafts is 80 fixed an arm 61 which is connected by a rod 62 to a crank arm 63 (Fig. 35) on a shaft 64 which is aligned with the shaft 43. On the shaft 43 is an arm 65 carrying a pin 66 that underlies an arm 67 fixed on the shaft 64. 85 It will be seen that when the shaft 43 is turned to apply the creel brakes, the contact bars 56 will be withdrawn from the openings 59. As hereinbefore stated, the brake for the beam A is so adjusted that the beam 90 shall coast a little less than any of the cheeses, the resulting slack being taken up by the descent of the detectors 51 in the tubes 55. When the contact bars 56 are moved out of the openings 59, the detector 95 belonging to the broken thread drops through its tube into a receptacle 68 (Fig. 40) in the form of a drawer. Lint is prevented from accumulating at the detectors by means of an air blast induced by any suitable means, an air supply tube 68a (Figs. 1 and 3) being in communication with one end 100 of the drawer 68. As shown in Figs. 40 and 41, the lower open ends of the tubes 55 extend into the drawer.

105 After an application of the cheese brakes, the shaft 43 is reset by means of a hand lever 69 (Fig. 4) pivoted at 70 and engaging a link 71 pivoted to the bell crank 44. The parts 69 and 71 are united by a pin-and-slot 110 connection, so that the bell crank 44 may move under the influence of the spring 45 without moving the hand lever. After the machine has stopped by reason of thread breakage, the operator uses the lever 69 to 115 restore the bell crank 44, the shaft 43, and the rod 40 to normal or running position. The operator then raises the weight 38 and engages the hanger 39 with the rod 40. As soon as said weight is lifted, a weighted arm 120 72 (Fig. 46) fixed on the shaft 29 turns said shaft into normal position, thereby placing the arm 30 in normal position. Fixed on the shaft 29 is an arm 73. When the shaft 29 is turned into normal position, the arm 73 125 strikes a pin 74 fixed to a pawl 75, said pawl being fixed to the pivot pin 26. The pawl 75 is adapted to engage a ratchet wheel 76

fixed on the continuously rotating shaft 25. A spring 77 tends to hold the pawl either in or out of engagement with the ratchet wheel.

78 (Fig. 46) is a stop to determine the thrown-out position of the pawl. When the weighted arm 72 turns the shaft 29, the arm 73 strikes the pin 74, and moves the pawl 75 toward the rotating ratchet wheel 76, the spring 77 completing the movement of the pawl into engagement with said wheel. As soon as the pawl engages the wheel, the latter swings the bracket 24 up into normal position as shown in full lines in Fig. 12. As the bracket 24 approaches its normal position, the pin 74 rides up on a stationary cam plate 79, whereby the pawl 75 is withdrawn from the ratchet wheel, and the stud 28 is placed in position to stop against the projection 31. In the movement of the bracket 24 from the thrown-out position shown in full lines in Fig. 46 to the normal position represented in Fig. 12, the bars 7 are raised to lift the cheeses off the brake plates 13.

25 The warp beam A is herein shown as supported with its yarn mass in peripheral contact with a rotatory driving drum 80 (Figs. 1 and 3). The journals of the warp beam lie within bearings 81 formed on slides 82 that are vertically movable on the upright frame members 83. A roll 84 rests upon the yarn wound upon the beam. (See Figs. 3 and 23 to 26). This roll extends from one flange or head of the beam to the other. The 35 roll 84 is held in place by means of a plurality of yokes 85 attached to a bar 86 which is fixed to slides 87 vertically slidable upon the uprights 83. Antifriction rollers 88 are interposed between the roll 84 and the yokes 85. It will be seen that the yarn mass supports the roll 84, the bar 86 and the parts connected to said bar. In order that the roll 5 may touch the heads of the beam and thus bear upon the entire yarn mass, said 45 roll may be made extensible in any suitable way, as by providing the roll with an end section 84^a which is longitudinally slidable upon a cylindrical guide 84^b fixed in the main section of the roll. Said main section 50 and the end section are connected together by intermeshing square lugs 84^c on said sections so as to present a substantially unbroken surface to the yarn mass. A spring 84^d presses the ends of the two sections of the roll into contact with the beam heads. The weight of the roll 84 and the bar 86 serves to prevent coasting of the warp beam on the drum 80.

55 Rotatably mounted in the slides 87 is a shaft 89 (Figs. 19 to 22) having two pinions 90 90^a upon its end portions. These pinions mesh with vertical rack bars 91 fixed in the machine frame. Loosely mounted or pivoted on the shaft 89 is a bracket 92 carrying

a pinion 93 that meshes with a spur gear 65 wheel 94 fixed on the shaft 89. Rigidly connected to the pinion 93 is a spur gear wheel 95 which meshes with a pinion 96 supported by the bracket 92. Rigid with the pinion 96 is a brake disk and fly wheel 97. A lever 70 98 pivoted on the shaft 89 carries a brake shoe 99 adapted to bear against the periphery of the brake disk 97. To the bracket 92 is affixed a weighted arm 100. A spring 101 tends to hold the brake shoe 99 against the 75 disk 97. When the warp beam is at rest, the arm 100 is supported upon a pin 102 on an arm 103 rigidly connected to the adjacent slide 87. The leverage of the pinion 90 is so greatly reduced by the train of gears 94, 80 93, 95, 96 that the pressure of the shoe 99 is sufficient to hold the bar 86 and the roll 84 suspended.

85 As the yarn mass upon the warp beam increases in diameter, the slides 87 rise, thereby causing the shaft 89 and spur gear 94 to revolve. The braking means 97 99 offers so much resistance to the rotation of the pinion 93 that the spur gear 94 lifts said pinion (and with it the bracket 92 and 90 weighted arm 100) until the lever 98 stops against the pin 102. The friction between the disk 97 and the shoe 99 is thereby relieved just sufficiently to allow the disk to turn. It will be seen that the spring 101 and 95 the weighted arm 100, by their leverage, resist upward movement of the bar 86 and prevent downward movement thereof.

99 It will be seen that if the yarn mass is slightly eccentric, the brake means 97 99 will 100 resist upward movement of the roll 84 when the high point passes the drum 80 or the roll 84, whereby a wave-like motion is set up in the yarn mass from the high place to the low place, thus filling the latter. The 105 brake means 97 99 also prevent the bar 86 from descending when the low place reaches the drum 80, therefore the low place receives only the pressure of the roll 84. Thus eccentricity of the yarn mass is being continually corrected or prevented. A handle 104 on the disk 97 provides means for manually rotating the disk to raise the eccentricity-preventing means, when desired. The handle 104 can also be used in placing initial pressure on the warp beam. The beam-rotating drum 80 is fixed upon a shaft 105. This shaft is arranged to be driven at relatively high speed under normal conditions, and at a lower speed after a break has been 120 repaired and until the slack has been taken up and the operator has noted that everything is again in running order.

125 Referring to Fig. 6: Upon the shaft 105 is loosely mounted a drive pulley 106 carrying a belt (not shown) extending from an electric motor, a countershaft, or other suitable continuously-operating source of power.

Rigidly connected to the pulley 106 is a pinion 107 that meshes with a spur gear wheel 108 fixed to the shaft 25 (Fig. 5). The drive pulley 106 and the pinion are loose on 5 the shaft 105, and are free to move longitudinally on said shaft to a slight extent. Fast on the shaft 25 is a pinion 109 that meshes with a spur gear wheel 110 loosely mounted on the shaft 105. The gear wheel 10 110 is free to have a slight movement longitudinally of the shaft 105. Means is provided for clutching either the drive pulley 106 or the spur gear wheel 110 to the shaft 105, which means comprises a drum 111 15 fixed to the shaft 105 by a key 112. Fixed to the drum 111 are two friction flanges 113 114 arranged to lie at the sides of two friction flanges 115 116 fixed to the pulley 106 and the spur gear wheel 110, respectively. 20 The flanges 113 114 are so placed that when the flanges 113 115 are in contact, the flanges 114 116 are separated, and vice versa. On the periphery of the drum 111 are pairs of lugs 117 (Fig. 8) between which lie lugs 25 118 (Fig. 6) on a ring 119. Two friction flanges 120 121 have a screw-threaded connection with the ring 119 and are arranged for contact with the flanges 115 116. Being attached by means of screw threads, the 30 flanges 120 121 are adjustable to take up wear. They are locked in position by a spring-pressed key 122 (Figs. 8 and 10) lying in a recess in the ring 119 and adapted to enter any one of a plurality of recesses 123 in the 35 flanged members 120 121. The ring 119 is slidable transversely of the drum 111 to carry the flange 120 into contact with the flange 115, or the flange 121 into contact with the flange 116, or to place the flanges 40 120 121 in neutral (central) position. The means for sliding the ring 119 comprises a collar 124 slidable longitudinally of the shaft 105 and connected to a plurality of arms 125. Each of these arms is pivoted to 45 the lugs 117 on the drum 111, and has a cam or eccentric end lying between the lugs 118 on the ring 119. It will be seen that when the collar 124 is moved longitudinally of the shaft 105, the cam ends of the arms 125 50 will force the ring 119 to one side or the other or into neutral position. When the collar 124 is moved to the left, as in Fig. 6, the flange 115 of the drive pulley 106 is clamped between the flanges 113 and 120, 55 thus causing the shaft 105 to be driven at high speed; and when the collar 124 is moved to the right the flange 116 of the gear wheel 110 is clamped between the flanges 114 and 121, thus causing the shaft 60 105 to be rotated at low speed.

The means for sliding the clutch-operating collar 124 comprises a rod 126 extending into the shaft 105 (which is tubular for a portion of its length), one end of said rod 65 being connected to the collar 124 by a pin 127 extending through slots 128 in the shaft. The other end of said rod is engaged at 129 by a lever 130, the fulcrum 131 of which normally lies between a block 132 and a member 133. The lever 130 is connected at 70 134 by a link 135 to a crank arm 136 fixed on a shaft 137. Also fixed on the shaft 137 is a crank arm 138 which is acted upon by a spring 139 that tends to turn the shaft 137 in the direction to place the clutch collar 75 124 in neutral position and thus cut off the driving power from the warp beam. (See Fig. 9). The shaft 137 is normally held in the position wherein the drive pulley 106 is clutched to the shaft 105, by means of an 80 arm 140 fixed on the shaft 137 and held by the spring 139 against a locking pin 141. When said pin is withdrawn, the spring 139 turns the shaft 137 and the parts thereon into the position represented in Fig. 9. The 85 pin 141 is operated by means including a coupling 142 (Figs. 13 and 14) fixed to the pin 141 and connected to a lever 143 which is pivoted at 144. Said lever is connected by a rod 145 to a crank arm 146 (Figs. 5, 90 12 and 35) on the rock shaft 64. A spring 147 connected to said crank arm 146 tends to hold the locking pin 141 either in or out of operative position. The shaft 64 is turned in the direction to withdraw the locking pin 95 141 when the electromagnet 48 releases the bell crank 44 to the action of the spring 45. Thus it will be seen that when a thread breaks, the spring 45 will turn the shafts 43 and 64 to cause the drive to be cut off from the beam and to cause the cheese brakes to be applied.

Means is provided for placing the warp beam in slow rotation in order to enable the operator to find the end of the broken thread on the beam, and in order to take up slack after the break has been repaired. This means comprises a treadle 148 (Figs. 1, 3 and 4) carried by a shaft 149. As indicated in Fig. 1, the treadle extends along the front side of the drum 80, and is located in convenient relation to a platform 150 provided for the operator. To the shaft 149 is fixed an arm 151 (Fig. 6) which is attached to one end of a chain 152 running over a sprocket wheel 153, a weight 154 being connected to the other end of said chain. It will be seen from the drawings that the weight 154 tends to move the treadle 148 into its normal (uppermost) position, as in 105 Fig. 12. The sprocket wheel 153 is loose on the shaft 137. Fixed to said wheel is a disk 155 (Figs. 5 and 12^a) carrying a pawl 156 arranged to engage a ratchet wheel 157 fixed on the shaft 137. When the treadle 110 148 is depressed, the pawl 156 turns the shaft 137 in the direction indicated by the arrow in Fig. 7. If it be necessary to rotate the beam to find the thread end, the operator depresses the treadle far enough to swing 115 120 125 130

the crank arm 138 from the position shown in Fig. 9 to that indicated in Fig. 7; the collar 124 will thereby be moved to clutch the spur wheel 110 to the shaft 105, thus 5 rotating the warp beam at low speed. After the end has been found, the operator removes his foot from the treadle, whereupon the beam stops. After the thread has been repaired, and a detector placed upon the 10 thread, the operator again depresses the treadle to place the beam in slow rotation. After the slack has been taken up, the treadle is fully depressed, thereby swinging the crank arm 138 from the position illustrated in Fig. 7 to the normal or high-speed 15 position represented in Figs. 5 and 6. In order, however, that the transition from low speed or rest to high speed shall not be too rapid, I provide the mechanism to be next 20 described.

The block 132 is mounted in a slot 158 (Fig. 7) in the slide 133, the latter being fixed to a rod 159. Said rod is longitudinally reciprocable in bearings 160 161. The 25 sliding movement of the block 132 in one direction is limited by a stop screw 162, and in the other direction is yieldingly limited by a spring 163. The slide 133 is arranged to be reciprocated by means including three 30 alined shafts 164 165 166. The shaft 165 has a screw-threaded portion 167 which is engaged by a nut 168 non-revolubly held in the slide 133. When the screw 167 is rotated in one direction, the slide 133 will be 35 moved into the position shown in Fig. 7 and when the screw is rotated in the opposite direction the slide will be moved to the position indicated in Fig. 9. The shaft 164 is continuously driven by a belt 169 running over a pulley 170 fixed on the shaft 164 and a pulley 171 fast on a shaft 172. The last mentioned shaft is driven by a chain 173 (Figs. 6 and 12) extending over sprocket wheels on the shafts 25 and 172. The shaft 40 45 166 is driven in the direction opposite to that of the shaft 164 by a belt 174 running over pulleys 175 176 on the shafts 25 and 166. (See Figs. 5 and 6).

Upon each end of the shaft 165 are fixed 50 clutch disks 177 178 arranged to be engaged by similar disks 179 180 fixed on the adjacent ends of the shafts 164 166. The shafts 164 and 166 are alternately moved into driving relation to the shaft 165 by means of a 55 shifter rod 181 carrying forks 182 183 that engage said shaft 164 and 166. The shifter rod 181 is moved by an arm 184 fixed on a rock shaft 185. Loosely mounted on said shaft 185 is a bell crank lever 186 (Fig. 6) 60 provided with a lug 187 against which one arm of a bell crank lever 188 is pressed by a spring 189. The bell crank 188 is fixed on the shaft 185. The bell crank 186 is arranged to be moved by a cam 190 fixed on 65 the shaft 137. When the operator wishes

the beam to rotate at low speed, he depresses the treadle 148 until the shaft 137 is in the position shown in Fig. 7, thereby causing the warp beam to revolve at low speed, and causing the cam 190 (through the agency of 70 the bell cranks 186 and 188 and the spring 189) to place the clutch disks 178 180 in engagement with each other. The slide 133 is thereby moved away from the fulcrum 131, into the position shown in Fig. 7. When the 75 operator desires the beam to rotate at high speed, he turns the shaft 137 to place the crank arm 136 in the position represented at 136^a in Fig. 1^a, and to place the arm 140 against the pin 141, as in Fig. 6. This 80 places the point 134 in position for high speed, but the fulcrum 131 is moved by a spring 191 into the inner end of the slot 158, thus placing the point 129 in neutral or ineffective position, whereupon the beam stops 85 rotating. The movement of the shaft 137 into high-speed position also withdraws the point of the cam 190 from the bell crank 186, whereupon means to be later described act upon said bell crank to move the shaft 90 166 out of clutch with the shaft 165, and move the shaft 164 into clutch with shaft 165, thereby causing the slide 133 to move into the position shown in Fig. 6. In such movement of the slide, the fulcrum 131 is 95 also moved, thereby moving the point 129 into the position represented in Fig. 6 and causing the member 111 to be tightly clutched to the pulley 106. It will be seen that in the movement of the lever 130 from the position marked "Transition" in Fig. 1^a to that marked "High speed", the warp beam will be gradually, though comparatively rapidly, accelerated by reason of the increasing pressure of the flanges 113 and 120 against 100 the flange 115. As soon as the slide 133 has moved the fulcrum 131 into high-speed position, the clutch disk 179 is separated from the disk 177 by a fork 192 fixed to the rod 159 and pressing against a collar 164^a on 105 the shaft 164. A similar fork 193 on the other end of the rod 159 engages the side of the pulley 176 and moves the disk 180 away from the disk 178 when the slide 133 has reached the position shown in Fig. 7. 110 When the operator turns the shaft 137 from low-speed to high-speed position, a cam 194 (Figs. 13 and 14) engages the lever 143 and moves the pin 141 into position to detain the arm 140 in high-speed position. It 115 will be seen that the movement of the slide 133 from the position shown in Fig. 7 to that illustrated in Fig. 6 causes acceleration 120 of the warp beam. In order to control such movement of the slide 133, and thus prevent the warp beam from being accelerated so fast as to subject the threads to excessive tension, I provide means to be next described.

The roll 54 (Figs. 2, 3, and 16) is jour- 130

naled in movable bearing boxes 195. The bearing boxes 195 are slidable in guides 196 and are arranged to be moved by stems 197 connected to arms 198 fixed on a rock shaft 199. To said shaft are attached weighted arms 200 that urge the roll 54 against the sheet of threads. On one end of the shaft 199 is a crank arm 201 which is connected by a rod 202 to an arm 203. Rigid with the arm 203 is an arm 204 which is connected to the bell crank 186 by a rod 205. When the operator turns the shaft 137 into high-speed position, the weighted arms 200 place the roll 54 in normal position, and also tilt the bell 5
10 crank 186 to place the shaft 164 in driving relation to the shaft 165, thereby causing the slide 133 to move toward the position shown in Fig. 6. If at any time the warp beam should be rotated with excessive acceleration, the increased tension on the threads will cause the roll 54 to yield, such yielding movement being transmitted to the bell cranks 186 and 188, whereby the shaft 164 is uncoupled from shaft 165, thus stopping 15 the travel of the slide 133 and preventing further increase of acceleration. When the tension on the threads becomes normal, the weighted arms 200 again cause the shaft 164 to be clutched to the shaft 165. When 20 the slide 133 has moved the fulcrum 131 into high-speed position the fork 192 disconnects the shaft 164 from the shaft 165. It will be seen that the thread-controlled 25 roll 54 and its connections constitute a regulator or governor acting to control the acceleration of the warp beam and maintain it at approximately the desired point until full speed is reached.

I have now described the means for connecting the driving power to the warp beam and for disconnecting the power from the beam. When a thread breaks, it is desirable to stop the rotation of the beam as promptly as possible, but allowing a controlled amount of coasting, and for this purpose I provide a braking mechanism, one form of which is illustrated in Figs. 18 and 27 to 34. To the shaft 105 which drives the drum 80 is fixed a brake drum 206. The 40 drum 206 is arranged to be locked against rotation by means of a brake band composed of two sections 207 208 pivotally connected together and secured in the frame of the machine. The brake-band sections 45 are moved into operative position by means of a crank arm 209 pivoted to the section 208 at 210 (Fig. 27) and to a rod 211 at 212. Said rod passes freely through lugs 213 and 214 on the brake-band sections, and 50 is screw-threaded at its upper end to receive a nut 215 (Fig. 32). The nut 215 rests upon the lug 214. It will be seen that when the crank arm 209 is swung to the right (Fig. 27) the brake-band sections will

be drawn into contact with the periphery 65 of the drum 206. A spring 216 tends to separate the brake-band sections, and a spring 217 (Fig. 27) normally holds the upper section clear of the drum and against an adjustable stop 218. The crank arm 209 70 is connected by a rod 219 to an arm 220 fixed on the shaft 43, (Figs. 4 and 18). Thus when the electromagnet 48 is actuated to release the bell crank 44, the movement of the shaft 43 to place the clutch in neutral 75 position and apply the cheese brakes also applies the brake to the drum 206.

The extent of oscillation of the crank arm 209 is invariable, the brake-applying movement of said arm being limited by the extent of movement of the shaft 43, and the movement of said shaft under the action of the spring 45 being limited by contact of the upper end of the lever 143 (Fig. 13) with the cam disk 194. In order to automatically obtain any adjustment of the brake band which may be necessary to produce the proper amount of coasting of the beam, I provide three adjusting mechanisms. One of these mechanisms acts at 90 every stoppage of the beam, and tends to cause uniformity in the amount of coasting. Another of the adjusting mechanisms acts constantly, and serves to adjust the brake so as to shorten or lengthen the coasting as 95 required by changes in the momentum of the beam. The remaining adjusting mechanism acts continuously to adjust the first mentioned mechanism so as to prevent the first mentioned mechanism from neutralizing or tending to neutralize the action of the second mentioned mechanism. I will now describe the first mentioned mechanism.

221 (Fig. 28) is a ratchet wheel, the shaft of which is coupled by a sleeve 222 and 105 pins 223 to the nut 215. The ratchet wheel is arranged to be turned by a pawl 224 mounted on a slide bar 225. This bar is guided in a bearing 226 and a stud 227 extending through a slot 228 in the bar. A 110 spring 229 tends to move the bar in the direction to move the pawl away from the wheel 221. A crank arm 230 (Fig. 18) on the rock shaft 43 has a pin and slot connection with a rod 231 attached to the slide 115 bar 225. When said shaft is turned to place the clutch in neutral position and to apply the beam brake, the slide bar 225 will be moved and thus cause the pawl 224 to turn the wheel 221. The nut 215 will thereby be turned to draw up the rod 211 and tighten the brake band. On the slide bar 225 is a lug 232 which is arranged to be engaged by an arm 233 fixed upon a shaft 234. Said shaft is adjustably mounted within a tubular 120 sleeve 235, the latter being rotatably supported in the hub 236 of a spur gear wheel 237 that meshes with a pinion 238 on

the shaft 105. The hub 236 is rotatably supported in a bearing 239 in the machine frame. The arm 233 has a V-shaped tooth 240 (Fig. 34) adapted to engage a series of similar teeth 241 on the side of the spur gear wheel 237. A torsion and compression spring 242 attached at one end to the bearing 239 and at its other end to the tubular shaft 235 tends to slide the shafts 234 and 235 toward the left (Fig. 29) and thus place the arm 233 in engagement with the teeth 241. Said shafts are adjustably secured together by a pin 243 extending through a flange 244 on the shaft 234 and into a stop arm 245 adjustably clamped on the shaft 235. The spring 242 tends to hold the arm 245 against a stop pin 246. It will be seen that the tension of the spring 242 may be adjusted by adjusting the arm 245 relative to the shaft 235. When the machine is running, the stop arm 245 bears against the stop pin 246, the arm 233 being held out of engagement with the teeth 241 by a bell crank 247 bearing against the stud 234^a and operated from the rock shaft 43 through a crank arm 248 and a rod 249. When the shaft 43 is turned to place the clutch in neutral position and to apply the brake band to the drum 148 through the action of the arm 209, the bell crank 247 is withdrawn from stud 234^a, whereupon the spring 242 moves the arm 233 into engagement with the teeth 241.

As hereinbefore stated, the beam brake is designed to allow the beam to coast a little less than the cheese which coasts the least. Such coasting of the beam causes the pinion 238 to revolve, thereby turning the gear wheel 237 and the arm 233. When the beam has nearly completed the proper amount of coast, the arm 233 reaches the lug 232 on the slide bar 225 and moves said bar to the left (Fig. 28), thus imparting a movement to the wheel 221 through the pawl 224, and drawing up the rod 211 to tighten the brake band. The beam is thereby arrested after approximately the proper amount of coasting. When the shaft 43 is reset by the operator by means of the hand lever 69, the bell crank 247 moves the shafts 234 and 235 longitudinally, thus moving the arm 233 away from the teeth 241, whereupon the spring 242 returns the arm 233 to normal position, as in full lines in Figs. 29 and 33.

When the shaft 43 is thus reset, the spring 229 restores the slide bar 225 to normal position, in which movement the ratchet wheel 221 is rotated in a reverse direction by a pawl 250 mounted on the slide bar 225.

Normally the pawl 250 stands against a tooth of the ratchet wheel 221, and the pawl 224 is removed from the wheel, as shown in Fig. 28^a. When a thread breaks and the shaft 43 is operated, the crank arm 230 and the rod 231 move the slide bar 225 into the position shown in Fig. 28^b. In this movement the pawl 224 does not engage and turn the ratchet wheel. If the brake is properly adjusted to permit the desired amount of coasting of the beam, the arm 233 will swing up into engagement with the lug 232 and impart a further movement to the slide bar 225 to cause the pawl 224 to turn the ratchet wheel through the distance of one tooth or less in the direction to tighten the brake band, whereupon the beam will stop. If the brake is not properly adjusted, but allows the beam to coast too far, the pawl 224 turns the ratchet wheel through a greater distance. If the beam continues coasting until the lug 232 is forced against the bearing 226, the tooth 240 will be forced out of one tooth space in the wheel 237 and will spring into the next space, and will continue springing from tooth to tooth until the beam stops. When the shaft 43 is reset by means of the hand lever 69, the crank arm 230 and rod 231 move the slide bar 225 into the initial position (Fig. 28^a), in the course of which movement the pawl 250 turns the ratchet wheel 221 through the distance of one tooth or a fraction thereof in the direction to loosen the brake band. Thus it will be seen that if the brake band is adjusted to such a point that the beam does not coast far enough to allow the arm 233 to strike the lug 232, the pawl 250 will turn the ratchet wheel in the direction to loosen the brake band when the shaft 43 is reset. The momentum of the warp beam depends, of course, upon its velocity and its mass. Being driven by peripheral contact with the drum 80, the velocity of the beam gradually decreases as the yarn mass increases in diameter, but the effect of such decrease upon the momentum of the beam is counteracted to a greater or less extent by the increase in the mass of the yarn. The increase in the mass of the yarn may be sufficient to cause an increase of the momentum of the beam as the latter fills, although if the beam heads be sufficiently massive the reverse will be the case. Similarly, the momentum of the cheeses may increase or decrease as the cheeses are unwound, depending upon the relation of the mass of the cheese core to the mass of the yarn. In the following description I will assume (as was done in the statement of the objects of the invention) that the momentum of the beam increases as the beam fills, and that the momentum of the cheeses decreases as the cheeses are unwound. The braking effort of the cheese brakes decreases as the mass of the cheeses decreases. The rate of decrease of the braking effort being assumed to be less than the rate of decrease in momentum of the cheeses, the amount of coasting of the cheeses will

be a little less at each successive stop. On these assumptions, the beam should coast less when full than when empty.

I will now describe the mechanism that acts constantly to adjust the brake band so that the beam shall coast a little less at each successive stop. The brake band sections are supported upon a pivot 251 (Figs. 1, 17 and 18) rotatably mounted in bearings 252, 253. The brake band section 207 is carried by an eccentric portion 254 of the pivot. It will be seen that when the eccentric 254 is rotated downwardly from the position shown in Fig. 27, the brake band section 207 will be moved nearer to the periphery of the drum 206. The means for thus moving the eccentric as the yarn mass increases in diameter comprises an arm 255 adjustably connected to a plate 256 fixed on the pivot 251, said arm being connected to an arm 257 through the medium of a rod 258. The arm 257 is fixed on the rock shaft 18. The arm 17 on said shaft is connected to an arm 259 fixed on a rock shaft 260 (Fig. 4) by means of a rod 261. On the shaft 260 is fixed an arm 262 which is attached through a link 263 to one of the slides 87. It will be seen that as the yarn mass on the beam increases in diameter, the eccentric 254 will be moved to adjust the brake band so that the beam shall coast a little less at each successive stop. In order to prevent the pawl 250 from neutralizing or tending to neutralize the effect of the action of the eccentric 254, I provide means for continually adjusting the normal position of the arm 233 so that said arm shall strike the lug 232 earlier at each successive stoppage. For this purpose, the stop pin 246 is mounted on a plate 264 which is arranged to be adjustably secured by a set screw 265 to an arm 266 rotatable on the shaft 235. The arm 266 is connected through a rod 267 to the arm 257 (Figs. 4 and 18). It will be seen that as the yarn mass on the beam grows larger, the stop pin 246 will be moved toward the right (Fig. 31), thereby bringing the normal position of the arm 233 nearer the lug 232. Thus the moment when the arm 233 begins to act to tighten the brake band is advanced in accordance with the decrease in momentum of the cheeses.

I have now described the various mechanisms of the machine. It will be apparent that all parts thereof have been designed to permit of a very high winding speed.

It will be understood that the invention is susceptible of embodiment in many different forms.

I claim as my invention:

1. A warping apparatus having, in combination, means for rotating a warp beam, a clutch which controls the beam-rotating

means, a pivoted lever connected to said clutch, a treadle and connections for placing a fulcrum of said lever in position for high speed, means for swinging said lever on said fulcrum to throw in the clutch, a roller yieldingly pressed against the threads being wound, and connections between the roller and the lever-swinging means for controlling the latter.

2. A warping apparatus having, in combination, a creel for rotatively supporting a plurality of independent yarn supplies, a warp beam to draw yarn from the supplies, a series of combined stop-motion and slack-take-up members each carried solely by one of the threads being wound on the beam, and a stop-motion element movable into and out of the path of the slack-take-up movement of said members.

3. A warping apparatus having, in combination, a creel; beam-rotating means; brakes permitting coasting of the yarn masses in the creel; a brake permitting the beam to coast a little less than the yarn masses; individual slack-take-up members, each supported upon one of the threads; and a separate tube within which each slack-take-up member may descend to take up the slack caused by the excess coasting of the yarn masses.

4. A warping apparatus having, in combination, means for winding a thread, a detector supported upon the thread, a stop-motion member normally lying in the path of descent of the detector, and means for withdrawing said member from the path of descent of the detector to allow the detector to descend to a point below the normal position of the stop-motion member to take up slack in the thread.

5. A warping apparatus having, in combination, means for winding a plurality of threads; a detector supported upon each thread; an individual tube for each detector; an electric contact bar normally lying in the path of descent of the detectors in said tubes; stopping means controlled by said contact bar; and means controlled by the stopping means for withdrawing said bar from the path of descent of the detectors to allow the detectors to descend in said tubes to a point below the normal position of the contact bar to take up slack in the threads.

6. A warping apparatus having, in combination, a friction drum for supporting and rotating a warp beam; a normally idle brake acting upon said drum to control the amount of coasting of the beam; and beam-controlled means for adjusting the brake.

7. A warping apparatus having, in combination, a friction drum for supporting and rotating a warp beam; a normally idle brake acting upon said drum to control the amount

- of coasting of the beam; means for adjusting the brake; and means in contact with the yarn mass on the beam for actuating said adjusting means.
5. 8. A warping apparatus having, in combination, a friction drum for supporting and rotating a warp beam; a normally idle brake acting upon said drum to control the amount of coasting of the beam; means for adjusting the brake; and means movable in accordance with changes in the diameter of the yarn mass on the beam, said last mentioned means being arranged to actuate the brake-adjusting means.
10. 9. A warping apparatus having, in combination, a friction drum for supporting and rotating a warp beam; a normally idle brake acting upon said drum to control the amount of coasting of the beam; means movable in accordance with changes in the diameter of the yarn mass on the beam; and two brake-adjusting devices actuated by said movable means.
15. 10. A warping apparatus having, in combination, a friction drum for supporting and rotating a warp beam; a normally idle brake acting upon said drum to control the amount of coasting of the beam; a brake-adjusting device; a brake-adjusting mechanism; means for adjusting said adjusting mechanism; and beam-controlled means for actuating said adjusting device and said adjusting means.
20. 11. A warping apparatus having, in combination, a friction drum for supporting and rotating a warp beam; a brake disk connected to said drum; a brake element adapted to engage said disk; and beam-controlled means for adjusting the normal position of said brake element.
25. 12. A warping apparatus having, in combination, means for supporting and rotating a warp beam; a brake disk associated with said rotating means; a brake element adapted to engage said disk; a pivotal support for said brake element; and beam-controlled means for adjusting the position of said pivotal support.
30. 13. A warping apparatus having, in combination, means for supporting and rotating a warp beam; a brake disk associated with said rotating means; a brake element adapted to engage said disk; a pivotal support for said brake element; and means movable in accordance with changes in the diameter of the yarn mass on the warp beam for adjusting the position of said pivotal support.
35. 14. A warping apparatus having, in combination, means for supporting and rotating a warp beam; a brake to control the amount of coasting of the beam; a screw and nut for adjusting the brake; a pawl and ratchet wheel for adjusting the nut and the screw with relation to each other; and an arm operatively connected to the beam and movable in the coasting of the beam for actuating said pawl.
40. 15. A warping apparatus having, in combination, means for supporting and rotating a warp beam; a brake to control the amount of coasting of the beam; a screw and nut for adjusting the brake; a pawl and ratchet wheel for adjusting the nut and the screw with relation to each other; an arm operatively connected to the beam and movable in the coasting of the beam for actuating said pawl; and means for adjusting the initial position of said arm.
45. 16. A warping apparatus having, in combination, means for supporting and rotating a warp beam; a brake to control the amount of coasting of the beam; a screw and nut for adjusting the brake; a pawl and ratchet wheel for adjusting the nut and the screw with relation to each other; an arm operatively connected to the beam and movable in the coasting of the beam for actuating said pawl; and beam-controlled means for adjusting the initial position of said arm.
50. 17. A warping apparatus having, in combination, means for supporting and rotating a warp beam; a brake to control the amount of coasting of the beam; means for disconnecting the rotating means from the beam; a pawl and ratchet device for adjusting the brake; said device comprising two oppositely-acting pawls; means operatively related to the beam and actuated in the coasting of the beam for actuating one of said pawls to tighten the brake; and means for actuating the other pawl to loosen the brake.
55. 18. A warping apparatus having, in combination, means for supporting and rotating a warp beam; a brake to control the amount of coasting of the beam; a shaft and connections for disconnecting the rotating means from the beam; a pawl and ratchet device for adjusting the brake, said device comprising two oppositely-acting pawls; means for actuating one of said pawls to tighten the brake; means for resetting said shaft; and a connection between the shaft and the other pawl for actuating the latter to loosen the brake in the resetting movement of said shaft.
60. 19. A warping apparatus having, in combination, means for supporting and rotating a warp beam; a brake disk arranged to rotate with the beam; a brake element arranged to engage said disk; means for adjusting the position of said brake element; and an arm operatively connected to the beam and operated in the coasting of the beam for actuating said adjusting means.
65. 20. A warping apparatus having, in combination, means for supporting and rotating a warp beam; a brake disk arranged to rotate with the beam; a brake element arranged

to engage said disk; a pawl and ratchet device for adjusting said brake element, and means operatively related to the beam and operated in the coasting of the beam for actuating said pawl and ratchet device.

21. A warping apparatus having, in combination, means for supporting and rotating a warp beam; a brake disk to rotate with the beam; a brake element arranged to engage said disk; a pawl and ratchet device for adjusting said brake element; an arm arranged to actuate said pawl and ratchet device; means for disconnecting the rotating means from the beam; and means operated by said disconnecting means for placing said arm in driven connection with the disk.

22. A warping apparatus having, in combination, means for supporting and rotating a warp beam; a brake disk arranged to rotate with the beam; a device for adjusting the brake; an arm for actuating said device; a wheel driven with said disk, said wheel and arm having a common axis, said arm being adapted to engage said wheel and rotate therewith; a spring tending to establish inter-engagement between the arm and the wheel; means for disconnecting the beam-rotating means from the beam; and means actuated by said disconnecting means for releasing the spring to action.

23. A warping apparatus having, in combination, means for supporting and rotating a warp beam; driving means for said beam-rotating means; a friction clutch between the driving means and the beam-rotating means; means for gradually throwing in the clutch; and means operated by the tension of the threads being wound for controlling the means for throwing in the clutch.

24. A warping apparatus having, in combination, means for supporting and rotating a warp beam; driving means for the beam-rotating means; a friction clutch between the driving means and the beam-rotating means; means for gradually throwing in the clutch; a roller over which the threads run; means urging the roller against the threads; and a controlling connection between said roller and the means for throwing in the clutch.

25. A warping apparatus having, in combination, a friction drum for supporting and rotating a warp beam, means to drive the drum, a treadle which controls the driving means, and means interposed between the treadle and the driving means for preventing excessive acceleration of the beam, said preventing means including a roller yieldingly pressed against the treads being wound.

26. A warping apparatus having, in combination, an element for rotating a warp beam; a drive wheel; a low-speed wheel; back gear connecting said wheels; a friction clutch member movable to connect

either of said wheels with the beam-rotating element and means for controlling the movement of said clutch member to regulate the degree of frictional engagement with the drive wheel.

27. A warping apparatus having, in combination, an element for rotating a warp beam; a drive wheel; a low-speed wheel; a friction clutch member movable to connect either of said wheels with said beam-rotating element; and means operated by the tension of the threads being wound for regulating the degree of frictional engagement between said clutch member and the drive wheel.

28. A warping apparatus having, in combination, a combined stop-motion and slack-take-up member adapted to be supported upon a thread, a relatively long guide for said member, one end of said guide being adjacent to the thread, and coöperating stop-motion means movable into and out of operative relation to said guide and located relatively near the thread.

29. A warping apparatus having, in combination, means for supporting and rotating a warp beam, a high-speed driving element, a low-speed driving element, a clutch arranged to connect the beam-rotating means with either of said elements, and thread-controlled means for operating said clutch to connect the beam-rotating means with the high-speed driving element.

30. A warping apparatus having, in combination, means for supporting and rotating a warp beam; a member bearing against the yarn mass on the warp beam; an arm pivoted with relation to said member; a brake disk mounted on said arm; means for rotating said disk as the yarn mass increases in diameter; a brake element co-acting with the brake disk; means holding said brake element in frictional engagement with the disk to prevent downward movement of said member; and means acting in the upward movement of said member to relieve such frictional engagement.

31. A warping apparatus having, in combination, means for supporting and rotating a warp beam; a member bearing against the yarn mass on the warp beam; a pinion supported to travel with said member; a stationary rack bar; a bracket pivotally mounted on the axis of said pinion; a brake disk rotatably mounted on said bracket; a co-acting brake arm pivotally mounted on the axis of said pinion; a connection between the pinion and the brake disk for rotating the latter; means tending to hold the brake lever and the brake disk in frictional engagement; and a stop arranged to travel with said member and arranged to be engaged by said brake lever for relieving the frictional engagement between said arm and said disk.

32. A warping apparatus having, in combination, means for supporting and rotating a warp beam; a high-speed driving element; a low-speed driving element; a clutch arranged to connect the beam-rotating means with either of said elements; and thread-controlled means for operating said clutch to cause a gradual acceleration.

33. A warping apparatus having, in combination, means for rotating a warp beam; a high-speed driving element; a clutch member connected to the beam-rotating means, a pivoted lever connected to said clutch member; means for placing a fulcrum of said lever in position for high speed; and thread-controlled means for swinging said lever on said fulcrum to place the clutch member in engagement with said driving element.

34. A warping apparatus having, in combination, means for rotating a warp beam; a high-speed element; a low-speed driving element; a clutch member arranged to connect the beam-rotating means with either of said elements; a lever connected at one end to said clutch member; said lever having a fulcrum at a point between its ends; means for varying the position of said fulcrum; and thread-controlled means engaging the other end of said lever for moving said lever on said fulcrum to operate the clutch member.

35. A warping apparatus having, in combination, means for rotating a warp beam; a brake for the beam comprising a brake drum and a brake band; devices for applying and releasing the brake band, said band comprising a plurality of sections, one of which is pivotally mounted; and thread-controlled means for adjusting the pivot for said pivotally mounted section to vary the position of the pivoted section with relation to the brake drum.

36. A warping apparatus having, in combination, means for rotating a warp beam; a brake for the beam comprising a brake drum and a brake band; devices for applying and releasing the brake band; said band comprising a plurality of sections, one of which is pivotally mounted; and means controlled by the size of the yarn mass on the warp beam for adjusting the pivot for said pivotally mounted section to vary the position of the pivoted section with relation to the brake drum.

37. A warping apparatus having, in combination, means for rotating a warp beam, a starting member which controls the beam-rotating means, and thread-controlled means interposed between the starting member and the beam-rotating means for preventing excessive acceleration of the beam.

38. The combination of devices for rotating a warp beam and for supporting the beam for a movement of translation; a wheel

arranged to be rotated through a movement of translation of the beam; a brake resisting movement of said wheel; and means for automatically relieving the pressure of the brake.

39. The combination of means for supporting a warp beam for a movement of translation; a slide arranged to be moved through a movement of translation of the beam; a pinion carried by said slide; a stationary rack meshing with said pinion; a bracket pivotally mounted on the axis of the pinion; a spur gear wheel fixed with relation to said pinion; a pinion rotatably mounted on said bracket and meshing with said spur gear wheel; means yieldingly resisting rotation of the second mentioned pinion; and means on said slide arranged to release the second mentioned pinion to rotation when said bracket is pivotally moved.

40. A warping apparatus having, in combination, means for rotating a warp beam, a treadle which controls the beam-rotating means, and thread-controlled means interposed between the treadle and the beam-rotating means for preventing excessive acceleration of the beam.

41. A warping apparatus having, in combination, means for rotating a warp beam, driving means for said beam-rotating means, a clutch between the driving means and the beam-rotating means, a treadle for operating the clutch, and thread-controlled means interposed between the treadle and the clutch for preventing excessive acceleration of the beam.

42. A warping apparatus having, in combination, means for rotating a warp beam, driving means for said beam-rotating means, a clutch between the driving means and the beam-rotating means, a starting member for operating the clutch, and means interposed between the starting member and the clutch, and controlled by the tension of the threads being wound, for preventing excessive acceleration of the beam.

43. A warping apparatus having, in combination, means for rotating a warp beam, a clutch which controls the beam-rotating means, a lever for operating the clutch, a starting member for moving said lever, and thread-controlled means for moving said lever.

44. A warping apparatus having, in combination, means for supporting and rotating a warp beam; a brake to control the amount of coasting of the beam; means acting constantly to adjust the brake as the beam fills; means acting at each stop to adjust the brake; and means to prevent the second mentioned adjusting means from neutralizing the effect of the action of the first mentioned adjusting means.

45. A warping apparatus having, in com-

5 bination, a friction drum for supporting and rotating a warp beam; a normally-idle brake acting upon the drum to control the amount of coasting of the beam; and means acting constantly to adjust the brake as the beam fills.

46. A warping apparatus having, in combination, a friction drum for supporting and rotating a warp beam; a normally-idle 10 brake acting upon the drum to control the amount of coasting of the beam; and means for automatically adjusting the brake.

47. A warping apparatus having, in combination, means for supporting and rotating a warp beam; a brake to control the 15 amount of coasting of the beam; and means acting at each stoppage of the beam for automatically adjusting the brake.

48. A warping apparatus having, in combination, means for rotating a warp beam, a clutch which controls the beam-rotating means, a pivoted lever connected to said clutch, means for placing a fulcrum of said

lever in position for high speed, and thread-controlled means for moving said lever on 25 said fulcrum to throw in the clutch.

49. A warping apparatus having, in combination, a creel for supporting a plurality of yarn supplies for rotation independently of each other, a warp beam to draw yarn 30 from the supplies, a series of combined stop-motion and slack-take-up members each held by one of the threads being wound on the beam, and beam-stopping means arranged to coact with one of said members which 35 has been released by its thread, the remaining members moving to take up slack caused by coasting of the yarn supplies when the beam stops.

In testimony whereof I affix my signature 40 in presence of two witnesses.

HOWARD D. COLMAN.

Witnesses:

EARL C. CARLSON,
GEORGE L. CHINDAHL.

It is hereby certified that in Letters Patent No. 1,209,122, granted December 19, 1916, upon the application of Howard D. Colman, of Rockford, Illinois, for an improvement in "Warping Apparatus," errors appear in the printed specification requiring correction as follows: Page 1, line 99, for the word "supplied" read *applied*; page 10, line 59, for the word "susceptable" read *susceptible*; page 12, line 59, claim 25, for the word "treads" read *threads*; and that the said Letters Patent should be read with these corrections therein that the same may conform to the record of the case in the Patent Office.

Signed and sealed this 23d day of January, A. D., 1917.

[SEAL.]

F. W. H. CLAY,
Acting Commissioner of Patents.
